UNITED STATES PATENT OFFICE.

WALLACE E. MEYERS, OF NEW YORK, N. Y.

GLOVE.

Application filed August 19, 1927. Serial No. 214,173.

This invention relates to improvements in gloves and more particularly to a glove having an improved arrangement of ornamental cuff which is capable of assuming various positions and which may be of contrasting colors on opposite sides so as to permit the user of the glove to give to the cuff and hence to the finish of the glove various shapes and designs.

10 A further object is to provide a glove of this character which is neat and attractive in appearance and strong and durable in use.

With these and other objects in view, the invention consists in certain novel features of construction and combinations and arrangements of parts which will be more fully hereinafter described and pointed out in the claim.

20 In the accompanying drawings—

Figure 1 is a view in elevation of my improved glove;

Figure 2 is an exaggerated view in section, on the line 2—2 of Figure 1;

25 Figure 3 is a fragmentary view in elevation, showing the glove, with the cuff portion thereof in a different position from that shown in Figure 1;

Figure 4 is an exaggerated view in section, 30 on the line 4—4 of Figure 3;

Figures 5 and 6 are views similar to Figures 1 and 2, respectively, illustrating the cuff of the glove in a still different position.

1 represents the glove, and 2 the cuff there-
35 of. This cuff 2 is secured to the edge of the glove 1 by a line or lines of stitching 3 which are located intermediate the edges of the cuff 2. The edges of the cuff 2 may be ornamented by stitching or embroidery 40 or decorated in any manner desired, and it is preferable that the cuff be of two thicknesses of material which may be

of different colors, or the inner face of the cuff may be of one color and the outer face of another, this effect being derived in any 45 desired way.

It is of course to be understood that the cuff is flexible and foldable on the lines of stitching 3 so that the cuff may lie flat against the outer portion of the glove, as 50 shown in Figures 1 and 2; may have its upper portion folded down over its outer portion, as shown in Figures 3 and 4; or may be folded within the glove proper, as 55 shown in Figures 5 and 6. Furthermore, the cuff may be folded in other ways desired to give a finish to the wrist portion of the glove to suit the desire of the user.

I of course do not limit myself to the materials nor to the exact manner of fold 60 but desire to cover broadly the idea of connecting the cuff to the edge of the glove in such a manner that the cuff may be folded or turned in different ways.

Various changes and alterations might be 65 made in the general form of the parts de-
scribed without departing from the spirit of the invention and hence I do not limit myself to the precise details set forth but consider myself at liberty to make such 70 changes and alterations as fairly fall within the spirit and scope of the appended claim.

I claim:

As a new article of manufacture, a glove and a cuff thereon, said cuff secured to the 75 edge of the glove by a line of stitching located intermediate the edges of the cuff whereby the cuff may be reversed and folded to vary the appearance of the same.

Signed at New York city, in the county of 80 New York and State of New York, this 16 day of August, A. D. 1927.

WALLACE E. MEYERS.
